SEMITAUTOMATIC STARTER CONTROL

Paul H. Maurer, Elmira, N. Y., assignor to Eclipse
Machine Company, Elmira Heights, N. Y., a
corporation of New York

Application April 10, 1933, Serial No. 665,313

7 Claims. (Cl. 290—38)

This invention relates to a semi-automatic starter control and more particularly to a device for causing the starting mechanism to operate upon closure of a manual control switch, which 5 will cause disconnection of the starting mechanism when the engine starts and which maintains the starting mechanism inoperative until the manual switch is opened and reclosed.

It is an object of the present invention to provide a semi-automatic starter control which is reliable and efficient in operation and of simple and economical construction.

It is another object to provide such a device which is independent of any engine function for 15 its control.

It is a further object to provide such a device which utilizes a function of the starting motor to cause disconnection when the engine starts.

It is another object to provide such a device 20 which is a comparatively small simple self-contained unit.

It is a further object to provide such a device in which the wiring installation is very simple and readily applied.

Further objects and advantages will be apparent to those skilled in this art from the following description taken in connection with the accompanying drawing in which:

Fig. 1 is a side elevation of a preferred form 30 of the starter control device with the parts in idle position, the casing being cut away to show the interior construction;

Fig. 2 is a similar end elevation of the same, the parts being shown in running position;

Fig. 3 is a section taken substantially on the line 3—3 of Fig. 2, the parts being shown in cranking position; and

Fig. 4 is a semi-diagrammatic illustration 40 showing the manner in which the device is used in connection with a conventional form of starting circuit, the parts being in idle position.

As stated generally in the objects of the invention, the purpose of this device is to provide a control unit which enables the operator to initiate the starting function by closure of the ignition switch of the engine, the cranking being automatically interrupted when the engine starts by a function of the starting motor, namely the reduction in the starting current due to the release of the cranking load, and which further includes an electric lock-out controlled by the ignition switch for preventing reclosure of the starting switch until the ignition switch has been opened by the operator and then reclosed.

Referring to Fig. 4 of the drawing there is il-

lustrated a conventional starting circuit for an internal combustion engine including a battery 1 grounded at 2 and connected by a lead 3 to an electromagnetic starting switch 4 which in turn is connected by a lead 5 to the starting motor SM which is grounded at 6 to complete the starting circuit. Means under the control of the operator for causing actuation of the starting switch 4 is provided in the form of a control circuit including battery 1, lead 7, manually operable 10 ignition switch 8, lead 9, electromagnet 11 of the starting switch, and three ground connections in parallel for completing the control circuit under various circumstances. The first ground connection includes lead 12, fixed contact 13 and a movable contact 14 which is mounted on a spring strip 15 and grounded as indicated at 16 whereby the control circuit is completed when contacts 13, 14 are in engagement which occurs when the starting switch 4 is open.

The second ground connection comprises lead 17, fixed contact 18 and movable contact 19 mounted on a pivoted armature 21 which is grounded as indicated at 22. Contacts 18 and 19 are normally maintained open by suitable 25 yielding means such as a spring 23, while a pole piece 24 is arranged adjacent armature 21 and is adapted to be magnetized by the starting current, in order to close contacts 18, 19 under the effect of the heavy starting current during cranking. This second ground connection thus cooperates to provide means for maintaining continuous cranking until the engine starts, and for then automatically opening the starting switch.

The third ground connection comprises a lead 35 26 and a resistance element 27 which is grounded at 28 whereby when both sets of contacts 13, 14 and 18, 19 are open, a small amount of current is permitted to traverse the electromagnet 11 so long as the ignition switch 8 is closed. The consequent weak energization of electromagnet 11 is utilized to maintain contacts 13, 14 open whereby the third ground connection cooperates in the control circuit to provide means for preventing reclosure of the starting switch until the ignition 40 switch is returned to idle position.

The starting switch 4 comprises a plunger 29 arranged to be actuated by the electromagnet 11 and carrying at one end a bridging contact member 31 insulated from the plunger and yieldably 50 maintained against a shoulder 32 thereon by suitable means such as a spring 33. The bridging element 31 is arranged to be brought into engagement with a pair of stationary contact members 34 and 35 when the electromagnet 11 is 55

energized by the closure of the control circuit through contacts 13, 14 or 18, 19.

For this purpose, the electromagnet 11 is provided with a central pole piece 36 (Fig. 1) and a U-shaped field member 37 presenting pole pieces 38 and 39 coplanar with the pole piece 36, and an armature 41 is suitably fixed to the plunger 29 which is arranged as shown to traverse the pole piece 36 centrally. Means such as a non-magnetic guide member 42 (Fig. 2) are provided for maintaining the armature 41 in alignment with the pole pieces 38 and 39. It will thus be seen that energization of the electromagnet 11 will cause the armature 41 to move downward against the action of a suitable releasing spring 43 which may be integral with the guide member 42, causing the bridging contact 31 to engage contacts 34 and 35, and thereafter compressing the spring 33 sufficiently to permit engagement of the armature 41 with the pole pieces 36, 38, and 39.

Means are provided for controlling contacts 13, 14 by means of the electromagnet 11 in order that such contacts may be opened when the starting switch is closed, and may be maintained open as long as the ignition switch is closed irrespective of the opening of the starting switch. As here shown, this means comprises a small auxiliary armature 44 seated in a recess in the main armature 41 and movably connected thereto as by means of guide members 45 and 46 fixed to the auxiliary armature 44 and traversing suitable openings in the main armature 41. The auxiliary armature 44 is normally held against the armature 41 by suitable readily yielding means such as the springs 47 and 48 mounted on the guides 45 and 46 and bearing against the top of the armature 41.

Auxiliary armature 44 is provided with a projection 49 adapted to engage the spring strip 15 and move contact 14 out of engagement with contact 13 when the auxiliary armature 44 is in engagement with pole pieces 36, 38 and 39.

It will be understood that the releasing spring 43 for the main armature 41 is sufficiently stiff so that the current which traverses the control circuit when resistance 27 is inserted therein by the opening of contacts 13, 14 and 18, 19 is not sufficient to retain the armature 41 in its normal or closed position. However, the springs 47 and 48 are made so light that the auxiliary armature 44 is retained in engagement with the pole pieces by such reduced flow of current so that the contact 14 will be maintained out of engagement with the contact 13 until the control circuit is completely deenergized by the opening of the ignition switch 8.

The magnetic control for the current controlled contacts 18, 19 is illustrated in Figs. 1, 2, and 3. It will be understood that when the starting switch 4 is closed, the contact members 34 and 35 and the bridging contact 31 form a loop as indicated by the dotted line in Fig. 4, the magnetic properties of which when traversed by the heavy cranking current are sufficient to accomplish the desired control function by means of a suitably designed magnetic circuit. As here illustrated this magnetic circuit comprises an L-shaped member 51 (Fig. 2) of suitable magnetic material which engages at one end with a plate 52 of magnetic material forming the base for the field member 37. A bracket 53 (Figs. 1 and 3) of magnetic material is suitably fixed to the plate 52 at the opposite side thereof, and carries the armature 21 and the spring mem-

ber 23. The opposite end of the magnetic member 51 is provided with an extension which is bent up into close proximity to the armature 21 to form the pole piece 24 whereby when the magnetic circuit including the L-shaped member 51, plate 52, and bracket 53 is sufficiently energized, the armature 21 will be attracted by pole piece 24 to close contacts 18, 19.

Suitable adjusting means indicated at 55 are provided for the spring 23 and it will be understood that the tension of the spring 23 is adjusted so that contacts 18, 19 will be held closed during the cranking operation, but will be released in consequence of the decrease of the starting current due to the release of the cranking load when the engine starts. A suitable back stop 56 is preferably provided to define the idle position of armature 21.

In operation, starting with the parts in the position illustrated in Figs. 1 and 4, closure of the ignition switch 8 completes the control circuit through the electromagnet 11 and contacts 13, 14 to the ground at 16 whereby the electromagnet is energized and attracts armatures 41 and 44, closing the starting switch and initiating the cranking operation. The rush of current through the starting circuit causes the contacts 18, 19 to be closed, thereby maintaining the control circuit grounded therethrough although the contacts 13, 14 are opened by the final movement of the auxiliary armature 44 which takes place after the engagement of the contact 31 with contacts 34 and 35 of the starting switch. Continuous cranking is thereby maintained until the engine starts, whereupon the decrease in the starting current permits the spring 23 to open contacts 18, 19. Since contacts 13, 14 have already been opened by the auxiliary armature 44, the resistance 27 is now placed in the control circuit, which reduces the current flow therethrough sufficiently to cause the main armature 41 to be released, thus opening the starting circuit. The magnetism remaining in the electromagnet 11 by reason of the reduced current flow therethrough is sufficient however to maintain the auxiliary armature 44 in its depressed condition whereby contacts 13, 14 are held open and reclosure of the starting switch thereby prevented. In order to obtain a restart, therefore, it is necessary for the operator to open the ignition switch and reclose the same whereupon the operation as above set forth is repeated.

Although one embodiment of the invention has been shown and described in detail, it will be understood that various changes may be made in the design and arrangement of the parts thereof, and other embodiments are possible without departing from the scope of the invention as defined in the claims appended hereto.

What is claimed is:

1. In a starter control for internal combustion engines, a starting circuit including a starting switch, a control circuit including an electromagnet for closing said starting switch and circuit controlling means, means whereby closure of the starting switch opens the circuit controlling means, and means energized by said electromagnet for holding said circuit controlling means open irrespective of the opening of the starting switch.

2. In a starter control for internal combustion engines, a starting circuit including a starting switch, a control circuit including an electromagnet for closing said starting switch and a circuit controlling means, said electromagnet having an

60

- armature to operate the starting switch and another armature to operate the circuit controlling means, and means to variably energize the electromagnet to selectively control said armatures.
5. 3. In a starter control for internal combustion engines, a starting circuit including a starting switch, a control circuit including an electromagnet for closing said starting switch and a circuit controlling means, said electromagnet having an armature to operate the starting switch and another armature to operate the circuit controlling means, means under the control of the operator for closing the control circuit whereby the electromagnet is energized to actuate its armatures
10. 15. to close the starting switch and open the circuit controlling means, and means for reducing the energization of the electromagnet to release the starting switch armature while retaining the circuit controlling armature.
20. 4. In a starter control for internal combustion engines, a starting circuit including a starting switch, a control circuit including an electromagnet for closing said starting switch and a circuit controlling means, said electromagnet having an armature to operate the starting switch and another armature to operate the circuit controlling means, means under the control of the operator for closing the control circuit whereby the electromagnet is energized to actuate its armatures
25. 30. to close the starting switch and open the circuit controlling means, means responsive to cranking load to hold the control circuit closed, said means being responsive to release of the cranking load when the engine starts to reduce the energization
35. of the electromagnet to release the starting switch armature while retaining the circuit controlling armature.
5. In a starter control for internal combustion engines a starting circuit including a magnetic starting switch, a control circuit therefor including circuit controlling means, means including an electromagnet for selectively operating the starting switch and said circuit controlling means, means for weakening said electromagnet to cause the starting switch to open when the engine starts, and means for deenergizing said electromagnet to operate the circuit controlling means. 10
6. In a semi-automatic starter control for internal combustion engines a starting circuit including a magnetic starting switch, a control circuit therefor including circuit controlling means, means including an electromagnet in said control circuit for selectively operating the starting switch and said circuit controlling means, means for weakening said electromagnet to cause the starting switch to open when the engine starts, and means under the control of the operator for 20 deenergizing said electromagnet to operate the circuit controlling means.
7. In a semi-automatic starter control a starting circuit including a magnetic starting switch, a control circuit therefor including a set of normally open contacts and a set of normally closed contacts in parallel, means responsive to energization of the magnetic starting switch for closing the normally open contacts and opening the normally closed contacts, means responsive to 30 self-operation of the engine for opening the normally open contacts, and means under the control of the operator for maintaining the magnetic starting switch sufficiently energized to hold open the normally closed contacts. 35
